UNITED STATES PATENT OFFICE.

GEORGE O. RESHAW, OF BENTON HARBOR, MICHIGAN.

FRUIT BASKET.

Application filed June 13, 1927. Serial No. 198,632.

In packing tree fruits for shipment by railway or truck, or for cold storage, bushel baskets have to a large extent replaced the use of barrels. There are two standard types of baskets used—the so-called "round bottom" basket and the flat bottomed form known as a "straight side" basket. The "round bottom" basket is less expensive and lighter, and its bottom affords effective ventilation between tiers of stacked baskets, for which purpose the central portion of the bottom is upwardly bowed. The basket being of flexible wood strips, this upwardly bowed or arched formation also provides a cushion for yieldably supporting the fruit and preventing bruising thereof. However, when the packed baskets are stacked in numerous tiers, the superposed weight often crushes the lower baskets, flattens their bottoms and thus destroys the ventilating spaces and the cushioning effect, and injures the fruit. For these reasons, the "straight side" basket is rapidly taking the place of the "round bottom" basket. The "straight side" type well resists the weight which it is called upon to support, but it is heavier and more expensive, and does not provide the effective ventilation and cushioning effect obtained with the "round bottom" construction.

It is the aim of my invention to provide a distinct improvement in the "round bottom" basket which will enable it to effectively meet all conditions encountered in its use, without danger of breakage, without impairing the ventilation and cushioning effects, and without materially increasing either its weight or its cost of production.

With the foregoing in view, the invention resides in the novel subject matter herein-after described and claimed, the description being supplemented by the accompanying drawings.

Fig. 1 is a side elevation partly broken away and in section, showing a basket improved in accordance with the present invention.

Fig. 2 is an enlarged detail sectional view 50 through a lower portion of the basket.

In the drawing above briefly described, the numeral 3 denotes a common form of fruit basket of the type known as a "round bottom" basket. The numeral 4 denotes the basket bottom, which bottom is provided with a peripheral portion 5 curving upwardly to the side wall 6. The central portion 7 of the bottom 4 is arched, providing a space 8 which affords ventilation between tiers of stacked baskets or between the floor and baskets resting thereon. As the basket is formed of thin wood strips of yieldable nature, this arched formation also forms a cushion for yieldably supporting the fruit and preventing bruising thereof. All of this is well known and is advantageous, and my invention aims to maintain the basket in this desirable form, by simple and inexpensive means.

The numeral 9 denotes a hoop having a relatively narrow inner peripheral portion 10 and a comparatively wide outer peripheral portion 11, well adapting it for engagement with the curved peripheral portion 5 of the basket bottom 4. The hoop is permanently secured to the basket and its lower edge is preferably flush or in the same plane with the lowest part of the portion 5 of the bottom 4. Thus, this hoop effectively supports the curved bottom portion 5 against downward crushing and against radial bulging, and consequently, the arched portion 7 of the bottom cannot flatten, nor can the lower end of the side wall 6 expand. Hence, under superposed weight, the lower portion 80 of the basket cannot become broken or distorted with danger of injuring the contained fruit, and the ventilating space 8 is preserved. Moreover, the cushioning effect of the arched basket bottom is maintained, and it is an important factor in shipping fruit without bruising.

In the preferred form of construction herein disclosed, the hoop 9 is of transversely stepped formation and the inner corners 12—13 of its relatively low and high steps, contact with the curved peripheral portion 5 of the basket bottom, corner 13 contacting with the portion 5 substantially at its junction 95 100

ture with side wall 6. The edges 12-13 and the line at which the portion 5 contacts with the supporting surface, provide three spaced lines of support for said portion 5, preventing distortion thereof. In order to provide this stepped formation and to produce an inexpensive construction, the inner and outer peripheral portions 10-11 of the hoop 9, are preferably formed from separate wooden hoops, as shown, the inner hoop 10 being of greater thickness than the outer hoop 11. The grain of the wood from which the hoops 10 and 11 are formed, preferably runs in different directions, producing a stronger construction than would otherwise result. The two hoops are rigidly secured together by the lower prongs 14 of a plurality of heavy staples 15, said lower prongs passing through both hoops 10-11 and being clinched as shown at 16. The upper prongs 17 of the staples 15, pass through the outer hoop 11 and through the basket, to secure the entire hoop structure 9 to said basket, the free ends of the prongs 17, being clinched as at 18.

The staples 15 perform a three-fold function. They tightly secure the inner and outer hoops 10-11 together, they rigidly secure the entire hoop structure 9 to the basket 3, and they effectively reinforce said hoop structure against splitting or breakage incident to rough handling.

It will be seen from the foregoing that an exceptionally simple and inexpensive, yet an unusually desirable construction has been provided for carrying out the object of the invention. On account of the advantages flowing from the exact construction disclosed, it is preferably followed. However, minor variations may be made and while in the present disclosure, the lower edge of the hoop 9 is in the same plane with the lowest part of the bottom portion 5, it might be merely disposed in the same plane with some other lowest part of the basket bottom, should the latter be of construction other than that disclosed.

I claim:

1. In combination with a flexible basket having an arched bottom whose peripheral portion is curved upwardly to the side wall of the basket; a hoop of stiffer material than the basket upon which said upwardly curved peripheral portion of said bottom is secured, said hoop contacting with said upwardly curved peripheral portion and having its lower edge in a common plane with the lowest part of said portion, thereby preventing flattening of the arched basket bottom and holding the lower end of said side wall against expansion.

2. In combination with a basket whose bottom is provided with a peripheral portion curved upwardly to the side wall of

the basket; a hoop upon which said curved peripheral portion is secured, said hoop having a continuous inner peripheral portion and a continuous outer peripheral portion projecting upwardly from said inner peripheral portion, adapting the hoop to the curvature of said peripheral bottom portion, the lower edge of said hoop being in a common plane with the lowest part of said curved peripheral bottom portion, whereby the basket bottom is held against flattening and the lower portion of the basket wall is held against expansion.

3. In combination with a basket whose bottom is provided with a peripheral portion curved upwardly to the side wall of the basket; a hoop upon which said curved peripheral portion of the basket bottom is secured, said hoop being transversely stepped to provide inner and outer continuous steps both contacting at their inner corners with said curved peripheral portion of the basket bottom, the lower edge of said hoop being in a common plane with the lowest part of said basket bottom, whereby the bottom is held against flattening and the lower portion of the basket wall is held against expansion.

4. In combination with a basket having an arched bottom whose peripheral portion is curved upwardly to the side wall of the basket; an inner relatively narrow hoop underlying and contacting at its inner upper corner with said curved peripheral portion between the lower and the upper extremities of the latter, an outer comparatively wide hoop surrounding said inner hoop and contacting therewith, said outer hoop projecting above said inner hoop and having its inner upper corner disposed in contact with the basket substantially at the juncture of said upwardly curved peripheral portion of the basket bottom with the side wall of said basket, and means securing the hoops together and to the basket, the lower edges of said hoops being in a common plane with the lowest part of said curved peripheral bottom portion, whereby contact of this portion with a supporting surface and contact of the same portion with said corners of said hoops, provide three lines of support for said portion to prevent distortion thereof, consequently holding the arched portion of the basket bottom against flattening and holding the lower end of the basket side wall against expansion.

5. In combination with a basket having an arched bottom whose peripheral portion is curved upwardly to the side wall of the basket; an inner relatively narrow hoop underlying and contacting at its inner upper corner with said curved peripheral portion between the lower and upper extremities of the latter, an outer comparatively wide hoop

surrounding said inner hoop and contacting therewith, said outer hoop projecting above said inner hoop and having its inner upper corner disposed in contact with the basket 5 substantially at the juncture of said upwardly curved peripheral portion of the basket bottom with the side wall of said basket, and staples having lower prongs securing the two hoops together and upper 10 prongs securing the upper portion of the wide hoop to the basket, the lower edges of said hoops being in a common plane with the lowest part of said curved peripheral bottom portion, whereby contact of this portion 15 with a supporting surface and contact of the same portion with said corners of said hoops, provide three lines of support for said portion to prevent distortion thereof, consequently holding the arched portion 20 of the basket body against flattening and holding the lower end of the basket side wall against expansion.

6. The combination of a basket comprising an approximately cylindrical body and a 25 rounded bottom having a restricted seating part, with a hoop formed of laminated strips with the outer strip having a greater width than the inner strip, said hoop encircling the basket where the rounded bottom 30 merges into the cylindrical body and with the outer strip of the hoop overlapping the wall of the cylindrical body and attached thereto, said hoop extending downward in cylindrical extension of the body with its 35 lower edge at the same level as the restricted seating part of the bottom, said hoop providing an annular seating base for the basket in offset relation to the rounded bottom and operating to prevent rocking of the basket 40 on its rounded bottom and said hoop also serving to reinforce the wall of the basket at the bend therein.

7. A hoop attachment for baskets comprising approximately rounded strips with the inner strip comparatively thick diametrically and narrow vertically and adapted to function as a support, the outer strip being comparatively flexible and wide, the 45 two strips being secured together with their edges overlapping and the outer strip extending beyond the inner strip to form a flexible skirt at the upper side of the hoop.

8. In combination with a flexible basket 55 whose bottom is provided with a peripheral portion curved upwardly to the side wall of the basket, a continuous hoop surrounding and secured to the lower portion of the basket to hold its side wall against expansion, said hoop having its lower edge disposed in the same plane as the lowest part of the basket bottom, and a second relatively narrow continuous hoop secured to the inner side of the first named hoop and having 60 its upper inner corner disposed in contact 125

with said upwardly curved portion of the basket bottom to support the latter against expansion and depression.

In testimony whereof I have hereunto affixed my signature. 70
